UNITED STATES PATENT OFFICE.

ROMAIN DE BERSAQUES, OF SEATTLE, WASHINGTON.

TOWEL-SERVICE MACHINE.

1,298,909.

Specification of Letters Patent.

Patented Apr. 1, 1919.

Application filed December 7, 1914, Serial No. 875,827. Renewed November 4, 1918. Serial No. 261,169.

To all whom it may concern:

Be it known that I, ROMAIN DE BERSAQUES, citizen of the United States, residing at Seattle, in the county of King and State of Washington, have invented a certain new and useful Improvement in Towel-Service Machines, of which the following is a specification.

My invention relates to improvements in machines for giving sanitary towel service, and the object of my invention is to provide a machine which shall be adapted to actuate a bolt of toweling in such manner that successive clean portions of it, each in the form of loops may become accessible for service as a towel and then, as such clean portions are successively soiled, it shall be rolled up compactly, one portion after another, until the whole bolt is soiled whereupon it may be removed from the machine which then may be supplied with a clean bolt to be actuated in like manner.

I accomplish this object by devices illustrated in the accompanying drawings in which Figure 1 is a view in front elevation of a machine embodying my invention as it would appear if the cover plates were removed; Fig. 2 is a view in vertical cross-section of the same on broken line B, B of Fig. 1, showing the actuating mechanism of my towel service machine in side elevation; Fig. 3 is a view in vertical cross-section on broken line A, A of Fig. 1; Fig. 4 is an enlarged fragmentary sectional view on broken line C, C of Fig. 1, certain parts being removed to better illustrate certain parts; Fig. 5 is an enlarged fragmentary sectional view on broken line D, D of Fig. 1; Fig. 6 is an enlarged fragmentary view in cross-section on broken line E, E of Fig. 1, certain parts being shown in elevation; Fig. 7 is an enlarged fragmentary view partly in cross-section and partly in elevation of a detail of my invention and Fig. 8 is an end view of a towel roller embodied in my invention.

Referring to the drawings throughout which like reference numerals indicate like parts, 10 is a casing within which is disposed the mechanism of my towel service machine, the numerals 11 and 12 are doors that are hinged to the front side of the casing 10 at its top and bottom edges respectively.

Within the casing 10 and extending cross-wise thereof are two towel rollers 13 and 14,

respectively, and four feed rollers 15, 16, 17 and 18 the feed rollers each preferably being provided with a finely corrugated rubber periphery 19 that engages with a towel 20 that is passed thereover.

Each of the rollers 13 and 14 is formed with a longitudinally disposed groove or channel 21 in its periphery and a small shaft or rod 22 is disposed to lie lengthwise within such groove 21 in the manner clearly shown in Figs. 1 and 3 whereby an end of the towel 20 may be drawn under the shaft 22 before the towel is wound on the roller 13 or 14 thus securing the towel to the roller.

The disposition of the towel 20 about the several rollers within my machine is clearly illustrated by the heavy broken line shown in Fig. 3, such towel 20 being first wound about the roller 13 thence passed downwardly around the roller 15, thence upwardly over the roller 16, thence outwardly through a slot 23 in the front of the casing 10 at the bottom of the door 11, thence it is permitted to hang downwardly and form a loop 24 for use as a hand or face towel, thence it is passed upwardly through a slot 25 and over the roller 18 thence downwardly around the roller 17 and thence upwardly to be secured to and wound about the roller 14 upon which roller 14 the soiled portion of the towel is wound as the clean portion is unwound from the roller 13, the several rollers and the towel 20 moving a short distance each time the machine is started.

The several rollers 13 to 18 inclusive are provided on each end with bearing studs 26 and slotted plates 27 and 28 are secured to the sides of the casing 10 to serve as journal plates for the studs 26 as clearly shown in Fig. 3 whereby the rollers easily may be removed.

Directly in front of the rollers 16 and 18 and secured to the doors 11 and 12, respectively, are spring pressed rollers 29 and 30 that are adapted to bear against the rollers 16 and 18 firmly to hold the towel against such rollers.

The stud 26 on one end of the roller 14 is flattened and is adapted to fit within a slot disposed in the end of a shaft 31 that is journaled for rotation in the side plate 28 and the studs 26 on one end of each of the other rollers 13, 15, 16, 17 and 18 are flattened and adapted to fit into the slotted ends of shafts similar to the shaft 31.

The shaft 31 is provided with a loosely mounted sleeve 32 that carries a fixedly secured worm-gearwheel 33 that is adapted to be engaged by a worm 34 that is connected with a motor 35 whereby it may be driven.

The sleeve 32 has a ratchet formed on one end thereof that is adapted to engage with a corresponding ratchet provided on a spring pressed sleeve 36 which sleeve 36 is slidably fastened to the shaft 31 by a slot and pin connection, more clearly shown in Fig. 6 whereby the roller 14 may be rotated in one direction only to wind the towel 20 thereon, the ratchet teeth on the sleeves 32 and 36, respectively, sliding over each other in case the direction of rotation of the motor 35 is reversed.

The towel 20, as it is wound upon the roller 14 serves as a belt to rotate the rollers 17 and 18 and the roller 17 is connected with a shaft 37 upon which is secured a sprocket wheel 38 that is connected by a sprocket chain 39 with another sprocket wheel 40 secured upon a shaft 41 that connects with the roller 16 whereby the rollers 16 and 17 are caused to rotate at the same rate of speed to unwind the same length of toweling from the roller 13 that is wound upon the roller 14 at each cycle of movement of the machine thus keeping the loop 24 always of the same length and the same amount of toweling exposed at all times.

The rollers 15 and 18 are connected with shafts 42 and 43, respectively, and such shafts 42 and 43 are connected with the shafts 41 and 37, respectively, by gearwheels 44, 45, 46 and 47 whereby all of the rollers 15, 16, 17 and 18 are caused to rotate at the same rate of speed.

The motor 35 is connected with a battery 50 by electrical conductors 51 and 52, the conductors 51 terminating in a contact member 53 on a movable arm 54 and the conductor 52 terminating in a fixed contact member 55 whereby when the arm 54 is moved sidewise the contact between the members 53 and 55 will be broken thus breaking the circuit formed by the conductors 51 and 52 and stopping the motor 35.

The arm 54 is articulated with a sleeve 56 that is mounted on a pivot shaft 57 and has its top end flexibly secured to the bottom end of a similar arm 58 that is articulated with a sleeve 59 that is mounted on a shaft 60 and the arms 54 and 58 are adapted to break the contact between the members 53 and 55 when they are moved out of alignment by a cam 62 that is provided on a shaft 63 which shaft 63 is resiliently mounted in the hollow hub of the gear wheel 64 and is adapted to be rotated by a gear-wheel 64. The gear wheel 64 is adapted to mesh with another gearwheel 65 provided on the shaft 42, as more clearly shown in Figs. 2 and 5.

The arms 54 and 58 are adapted to be moved to effect their release from the cam 62 by a push button 66, such arms, when released, being pressed outwardly by springs 67 and 68 to cause the members 53 and 55 to make contact and close the circuit formed by the conductors 51 and 52 thus starting the motor 35 and causing a short length of clean towel, preferably from one to two feet thereof, to be fed outwardly through the slot 23 and an equal length of soiled towel to be drawn inwardly through the slot 25, the motor 35 being again stopped by the action of the cam 62 which strikes the lever arm 54 and moves it to the position shown in Fig. 2, when the shaft 63 has made one complete revolution the amount of clean towel that is presented each time being governed by the relation of the gearwheels 64 and 65.

A ratchet wheel 69 is carried by the sleeve 32 and a similar ratchet wheel 70 is provided on a shaft 71 with which the roller 13 is connected and pawls 72 and 73 are secured to the arms 54 and 58 and adapted, when such arms are moved by the cam 62 into the position shown in Fig. 2 and the motor 35 is stopped by the breaking of the circuit formed by the wires 51 and 52, to engage with the ratchet wheels 69 and 70 to lock the rollers 13 and 14, a spring 74 being attached to the pawl 73 to bring the arms 54 and 58 into alignment when they are released from the cam 62 and to withdraw the pawls 72 and 73 from the ratchet wheels 69 and 70.

To prevent unreeling the towel 20 from the roller 13 by pressing the push button 66 and then pulling on the towel, in case the circuit formed by the wires 51 and 52 is broken or the motor 35 out of order, I have provided adjacent the slot 23 and in a position where the towel 20 passes thereover a spring pressed locking plate 75 of a cross-sectional shape clearly shown in Fig. 3, which locking plate 75 serves as a lever arm when a downward pull is exerted on the towel 20 and turns a shaft 76 upon which it is secured.

The shaft 76 extends through the wall of the casing 10 and has a crank arm 77 secured to its outer end which crank arm 77 is articulated with a U shaped link 78, more clearly shown in Fig. 4, that passes around the arm 54 whereby when the outer edge of the plate 75 is depressed by pulling downwardly on the towel the arms 54 and 58 will be moved into the position shown in Fig. 2 thus locking the rollers 13 and 14 and preventing the towel from being unwound.

79 is a spring pressed tension roller that is adapted to bear downwardly on the roll of toweling on the roller 13, such roller 79 being secured to a crank shaft 80 clearly shown in Fig. 1, and being adapted, when the towel is completely unwrapped from the roller 13, to drop downwardly past such

roller thus turning the shaft 80, the outer end 81 of which shaft 80 is formed L shaped and is interlocked with the peculiarly shaped end 82 of a vertically disposed shaft 83, as 5 more clearly shown in Fig. 7, in such manner that the shaft 83 is turned by the turning of the shaft 80.

The lower end of the shaft 83 is provided with an L shaped extension 84, more clearly 10 shown in Fig. 5 that bears against the end of the shaft 63 to move such shaft 63 and the cam 62 endwise and release the arm 54 to permit such arm 54 and the arm 58 to be moved sidewise by pressure of the springs 15 67 and 68 and make contact between the members 53 and 55 which contact may then be broken only by lifting the roller 79 to an elevated position as shown in Fig. 3, and moving the arm 54 so that it may again engage with such arm to move it outwardly 20 and break the contact between the members 53 and 55, the object of thus keeping the circuit closed being to permit the end of the towel 20 to be entirely wound upon the roller 25 14 when it is free from the roller 13.

In order that the circuit formed by the wires 51 and 52 may be broken when the towel 20 is completely wound upon the roller 14 I have provided on the shaft 31 a 30 gearwheel 86 that is adapted to mesh with another gearwheel 87 that is rotatably mounted on an arm 88 which arm is swingingly mounted on a shaft 89 and is adapted to be swung downwardly by the pressure of 35 a spring 90 when the shaft 89 is released to cause the gearwheels 86 and 87 to mesh with each other, such shaft 89 being released by the turning movement of the shaft 80 when the roller 79 is permitted to drop downwardly, the shaft 80, as clearly shown in Fig. 3, being connected with the shaft 89 by the lever arm 91 on the shaft 80, the lever arm 92 on the shaft 89, and the cable 93 that connects the ends of such two lever 45 arms 91 and 92.

The gearwheel 87 is provided with an outwardly projecting pin 94 that is adapted, when such gearwheel is rotated, to engage with and move a switch lever arm 95 thus 50 breaking the circuit formed by the conductor wires 51 and 52 and stopping the motor 35 after it has turned the roller 14 sufficiently to completely wind the last end of the towel thereon, the gearwheel 87 being 55 held in mesh with the gearwheel 86 and the circuit governed by the switch arm 95 remaining open until the roller 79 has again been raised, a spring 96 being associated with the gearwheel 87 to rotate such gearwheel 60 backwardly until the pin 94 strikes against the arm 88, the switch arm 95 being actuated by a spring 97 that causes it to resume a contact as soon as the wheel 87 is moved out of mesh with the wheel 86.

65 If desired a bell 98 may be secured to the

casing 10 as clearly shown in Fig. 2 and such bell may be rung by the blows of a clapper 99, as a signal that the machine is in operation, the clapper 99 being withdrawn from the bell 98 by the action of a pin 100 that projects from the side of the gearwheel 44 and being actuated by a spring 101 to strike a blow on the bell 98 when it is released by the pin 100.

To prevent the towel 20 being wound in 75 a wrong direction about the roller 13 and such roller 13 from being rotated in a wrong direction I have provided in the circuit formed by the conductor wires 51 and 52, a switch 102 that is adapted to be opened 80 and closed by the movement of a switch arm 103 that is fulcrumed on a pin 104 and is normally held in contact by a spring 105, such switch arm being so disposed in the path of a pawl 106, that is secured to the 85 ratchet wheel 70 as clearly shown in Fig. 2, that when the ratchet wheel 70 is rotated backward or in a contra-clockwise direction the pawl 106 will engage with the switch arm 103 to open the switch thus stopping 90 the motor 35 but when the ratchet wheel 70 is rotated in the right direction or clockwise, the pawl 106 will be deflected and move past the end of the switch arm 103 without moving such switch arm. 95

The operation of my towel service machine may be described as follows:

The machine is secured to the wall or placed upon a suitable support in a place where towels are to be supplied to the public, as in the toilet room of an hotel, and a strip of towel fabric is wound on the roller 13.

The outer end of the towel fabric 20 is then drawn downwardly around the rollers 105 15 and 16 and outwardly through the slot 23 to form a loop of clean toweling outside of the casing 10 such end then being passed upwardly through the slot 25 around the rollers 17 and 18 and being secured to the 110 roller 14 by passing the end thereof under the shaft 22 and turning such roller sufficiently to wind one thickness of towel over such shaft 22 to hold it down.

When the loop 24 of toweling becomes 115 soiled from use any one desiring clean toweling may push the button 66 on the side of the casing 10 thus closing the electric circuit in which is connected the motor 35 and causing such motor to drive the hereinbefore described mechanism through a certain predetermined number of revolutions to feed out clean toweling from the roller 13 and wind it on the soiled toweling on the roller 14. 120

The towel 20 being one long strip and being secured at both ends can not be carried away and clean toweling is always 125 easily accessible to any one that wishes it.

When the toweling is entirely unwound 130

from the roller 13 and wound on the roller 14 the rollers 13 and 14 may be easily taken out and the toweling removed from the roller 14 and a clean towel wound on the roller 13.

Obviously numerous changes in the mechanical parts of my device may be made without departing from the spirit of my invention or sacrificing any of its advantages,

10 What I claim is:

1. In a towel service machine of the class described, the combination with a casing that is provided with slots in its front side, of a towel roller rotatably mounted in the upper portion of said casing, another towel roller rotatably mounted in the lower portion of said casing, idler rollers disposed below each of said towel rollers, a motor connected with said lowermost towel roller, 15 means connecting said lowermost towel roller with each of said idler rollers, whereby all of said idler rollers may be caused to rotate at the same rate of speed to unwind a towel from said uppermost towel roller, 20 at the same rate of speed that said towel is wound upon said lowermost towel roller, and means for breaking the circuit of the 25

motor when the towel is completely wound on the receiving roller.

2. In a towel feeding machine, the combination with a casing, of a towel roller for clean towel fabric rotatably mounted in said casing, a towel roller for soiled towel fabric rotatably mounted in said casing, mechanism for actuating said towel rollers whereby successive short lengths of clean towel fabric from said first named towel roller may be exposed for use and similar successive short lengths of soiled towel fabric may be wound on said last named towel 40 roller, automatic means for winding the last end of said towel on said last named roller when said last end is released from said first named roller and automatic mechanism to stop said roller when said last end 45 is wound upon said last named roller.

In witness whereof, I, hereunto subscribe my name this 26th day of November A. D., 1914.
